United States Patent Office.

AMOS HADLEY, OF WASHINGTON, DISTRICT OF COLUMBIA, ASSIGNOR TO HIMSELF AND ROBERT CLENIGHEN, OF NEW YORK CITY.

Letters Patent No. 78,278, dated May 26, 1868.

IMPROVEMENT IN DOOR-INDICATORS.

The Schedule referred to in these Letters Patent and making part of the same.

TO ALL WHOM IT MAY CONCERN:

Be it known that I, AMOS HADLEY, of Washington, in the county of Washington, and District of Columbia, have invented a new and useful Improvement in Business-Registers or Door-Plates; and I do hereby declare that the following is a full, clear, and exact description thereof, reference being had to the accompanying drawings, and the letters of reference marked thereon, in which—

Figure 1 is a front view.

Figure 2 is a front view of the plate *d* and wheel *g*.

The nature of my invention consists in providing a neat and convenient method whereby any business man, when supplied with this article, can, by placing it over his desk or upon the outside of his office-door, readily set it to indicate his whereabouts, or the time at which he will return, thus affording the information desired by callers, thereby preventing their waiting, when the person desired will not return for some time, or preventing the going away of callers because the proprietor is out a moment, and has left no indication of the time he is to be absent. Also, making a neat and attractive business-card for an office or office-door.

Its construction and operation are as follows: The front, *a*, is made of thin metal or card-board, and of any desired size or form. It may have an ornamental frame or border around it, as seen at *b b*, fig. 1. On one side of the centre of the front piece *a*, I make an orifice, *e*, which is covered with mica to prevent the indicator from being tampered with. Over the orifice is placed the name of the proprietor, and upon other parts of the front, *a*, his business-card, office-hours, residence, &c. Back of and against the front piece *a* is placed a thin frame, *d*, and next to that a thin piece of wood, the same size of the front piece, this forming the back, thus leaving a thin or shallow space between the front and back, which is surrounded by the frame *d*. The front, *a*, frame *d*, and back are securely fastened together. In this space is placed a wheel, *g*, made of thin metal or card-board, which is revolved by a spindle, *f*, whose bearings are the front piece *a* and the back. The form of the wheel is shown in fig. 2. On the side of the rim, and on a line drawn from the centre of the wheel, are printed the numbers indicating the hours of the day or night, the days of the week, and "soon;" or upon which may be printed any other figures or words necessary to adapt the register more particularly to the convenience of any individual, or to any other uses. The rim of the wheel *g* is connected to the hub by bars or spokes, *h h*, as seen in fig. 2. These bars are of about the same width as the orifice *e* of the front, *a*, and upon the face of the said bars are printed the phrases, "Is out," "Is in," "Is at dinner," and "Is out of town," one phrase being upon each bar; or anything else may be placed upon them that would add to the convenience of the individual, or to other uses.

Opposite the orifice *e*, on the back, is printed the phrase, "Will be in at," (or any other desirable one,) which phrase shows through the orifice *e*, between the bars *h* of the wheel *g*, except when the bars *h* shall intervene between it and the orifice *e*, and exhibit one of the phrases thereon. The phrase "Will be in at," when showing through the orifice *e*, unites with the figures on the rim of the wheel *g*, thus indicating any hour or day, or when the proprietor will return, if out, or away from his place of business.

Used as a "register door-plate," fastened on the outside of a door, the spindle *f* passes through the door to the inside of the office, thus preventing it from being tampered with from the outside, but for use inside an office or for a front hall, the knob is on the face of the register.

Having thus fully described my invention, what I claim, and desire to secure by Letters Patent, is—

The rotating disk between the two stationary plates, all as shown and described, and for the purposes specified.

Witnesses:

G. A. C. SMITH,
T. C. THEAKER,

AMOS HADLEY.
